UNITED STATES PATENT OFFICE.

MAXIME BOUQUET, OF BROOKLYN, NEW YORK.

CUFF-BUTTON.

SPECIFICATION forming part of Letters Patent No. 366,644, dated July 19, 1887.

Application filed April 1, 1887. Serial No. 233,268. (No model.)

To all whom it may concern:

Be it known that I, MAXIME BOUQUET, of Brooklyn, Kings county, and State of New York, have invented a new and useful Improvement in Cuff-Buttons, of which the following is a specification.

My invention relates to that class of sleeve-buttons which are secured to the cuff by means of a spiral, and it is described in the following specification, and more specifically pointed out in the claim.

Figure 1 of the drawings is a piece of sheet metal which is cut ready to be bent, so as to form the shank and attaching-plate. Figs. 2 and 3 show, respectively, a bottom and side view of the button completed, the shank and spiral of which are formed from the sheet-metal piece of Fig. 1.

I take a piece of sheet metal and cut or stamp from it a piece of the form shown in Fig. 1. The part *c* is bent upward, so as to form a right angle at or about the point *d*. The part from *d* to *e* is then bent edgewise inward, so as to bring the angle at *d* about the center of the curve formed by the part *b*. The part *b* all the way round to the angle *d* thus forms a spiral, at the center of which the part *c*, which is to form the stem of the button, projects upward.

The extension *h* of the part *b* is bent inward slightly and so that it overlaps the part between *d* and *e*, and lies substantially in contact with it, so that the extension *h* has to be lifted slightly from the part of the spiral lying below it in order to insert the part *h* into the button-hole for the purpose of adjusting the

button in the cuff. This is clearly shown in Fig. 3. The extremity of the part or stem *c* is soldered or otherwise properly secured to the center of the button-head *a*, as shown in Fig. 3, 40 and when the button is thus completed it consists substantially of two parts—namely, the head *a* and the stem and spiral.

My improved sleeve-button contains many advantages, among which may be mentioned 45 the following: The spiral being made from a piece of sheet metal, comparatively little bending is required to form any part excepting turning up the shank. The result of this construction is that the metal is in its normal condition and is much more firm and resistant to bending than in a case where the spiral is formed by bending a straight piece of metal, as, for instance, a wire. Likewise the form into which the spiral is bent makes it firm and 50 easily to be applied, while not likely to catch in other articles of wear and not likely to be accidentally detached.

I claim—

A cuff-button composed of the head *a*, the 60 spiral and stem *b* *c*, the said spiral and stem being made of one continuous piece of metal bent in spiral form from sheet metal, substantially as described, and the extremity thereof, as *h*, bent inwardly, so as to overlap and substantially rest upon a portion of the spiral adjacent to the stem, substantially as described. 65

MAXIME BOUQUET.
